UNITED STATES PATENT OFFICE

167,393

TRAY FOR POSTING MACHINES OR THE LIKE

John H. Davis, Garland, and William L. Berkman,
Georgetown, Tex.

Application November 21, 1950, Serial No. 13,070

Term of patent 14 years

(Cl. D74—1)

To all whom it may concern:

Be it known that we, John Hester Davis and William L. Berkman, citizens of the United States and residents of Garland, in the county of Dallas and State of Texas, and Georgetown, in the county of Williamson and State of Texas, respectively, have invented a new, original, and ornamental Design for a Tray for posting machines or the like, of which the following is a specification, reference being had to the accompanying drawings, forming part thereof.

Fig. 1 is a perspective view of a tray for a posting machine or the like embodying the design; and

Fig. 2 is a side view thereof.

The fragmentary portion of a posting machine or the like, shown in broken lines in Figs. 1 and 2, are for illustrative purposes only.

We claim:

The ornamental design for a tray for posting machines or the like, as shown and described.

J. HESTER DAVIS.
W. L. BERKMAN.
